UNITED STATES PATENT OFFICE.

DRUMMOND WELBURN, OF ORLANDO, FLORIDA.

PORTABLE HOUSE.

SPECIFICATION forming part of Letters Patent No. 391,442, dated October 23, 1888.

Application filed August, 30 1887. Serial No. 248,327. (No model.)

To all whom it may concern:

Be it known that I, DRUMMOND WELBURN, of Orlando, in the county of Orange and State of Florida, have invented a new and useful Improvement in the Construction of Houses, of which the following is a specification.

My invention is an improvement in the construction of houses; and it consists in certain features of construction and novel combinations of parts, as will be hereinafter first fully described, and then pointed out in the claims.

In the drawings, Figure 1 is a vertical cross-section of my improved house. Fig. 2 is a detail view of one of the floor-sections. Fig. 3 is a detail view of one of the roof-sections. Fig. 4 is a detached cross-section on about line xx , Fig. 1. Fig. 5 is a detached section on about line yy , Fig. 1. Fig. 6 is a detached section on line zz , Fig. 1. Fig. 7 is an enlarged detail section showing one of the windows, and Fig. 8 is an enlarged section of the comb of the roof.

In the construction of my improved house I employ floor-joists A, two by six, which are set on edge four feet apart. These joists may be rested on the ground or on sills or other prepared foundation, as may be desired. In the upper sides of these joists, near their ends, I drive spikes a , such spikes being arranged one inch out from the edge of the floor when the latter is laid in the manner hereinafter described. The floor is laid on these joists A, and is formed in sections B, each two feet wide. Each section may be held together by the strips or cleats B', arranged in pairs sufficiently separated to embrace the joists A and steady them in position. At one end the strips extend at b past the edge of the section B, to which they are secured, and lap under the adjacent section, thus serving to secure such sections in close connection with each other. On the upper side of the floor, at each end, I secure a pair of cleats, C, set one inch apart and made two inches high, forming a groove one inch wide and two inches deep. These strips C extend at one end beyond the sections to which they are secured, the extensions c serving, in connection with the extensions b , to further brace the floor-sections together.

The gable ends D are formed in sections d two feet wide, and made of tongue-and-groove

stuff, novelty siding, or other suitable construction, and may be held together in similar manner to the floor-sections before described.

Cleats E and E' E' are employed to unite 55 the sections d , the cleat E being the base-cleat and the cleats E' the side cleats, the parts being united and forming a triangular-shaped bracing-frame. The side cleats, E' , are secured about eight inches in from the edges of the 60 gable, while the base-cleat E is about two inches from the bottom of the sections. The portion of the ends below the cleat E fits in the groove between the cleats C. The ends are further strengthened by a sliding clasp, F, forming 65 practically a box-clasp slipped over the apex of the end, and serving to clasp the sections firmly together and to the brace-cleats. This clasp F also forms the upper groove and guide of a sliding glass door, G, the lower end of 70 which door slides on the base-strip E of the triangular brace-frame, and is held in place by a board, E ^{2} , six feet long, fastened to the base-strip E, and rising one inch higher than such board.

The roofing sides G' are made of novelty siding in sections two feet wide, the boards of the sections being braced together in like manner to the sectional parts before described—such, for instance, as the floor and 80 gable ends. On the under side of and at each end of the roof-sections I provide cleats g in pairs, as shown, arranged one inch apart, and made two inches thick to form grooves one inch wide and two inches deep, which receive 85 the edges of the gable ends. I also provide two pairs of cleats, H, forming grooves, arranged midway between the ends and the center of the structure. These grooves receive rafters I, which are joined together under the 90 comb and rest on the floor over the floor-joists. These rafters are made of one-by-four stuff and set edgewise, so as to keep the roof sides from sagging. The lower sections of both sides are set edgewise on the joists A between the edges of the floor and the spikes a in the joists. These sides are held tightly in place by the spikes a and the floor by their hold upon the gable ends, and also by their hold upon the one-by-four rafters.

Each of the inside cleats of the roof extends at one end above the section to which it is se-

cured, lapping the adjacent one, so that each added section increases the force of the clutch or grip, by which all of the parts of the entire building are firmly held together.

5 For light and ventilation, in addition to the sliding glass doors at the end, the house has a swinging window, J, in each side. To exclude rain, a piece of tin, j, is inserted under the edge of the siding, forming a cap over and 10 beyond the window, and a similar piece, j', may be tacked to the lower edge of the sash.

Additional ventilation is secured by attaching the top section of one of the sides to the one next below by strap-hinges, so that in 15 sultry weather a pole may be used to open said section to let out the foul air. This hinged upper section should be four inches wider than the one opposite, so as to extend there-over and form a rain-proof comb. To form 20 the porch K, an additional joist A and plank four feet longer is all that is necessary, and where two houses are arranged close together a porch may extend between them, forming a passage-way, or by extending one porch a few 25 inches over another a wide platform will be provided between the two houses, by inclosing which an additional room may be pro- 30 vided, all forming practically a house with three rooms.

35 Manifestly, canvas, gum-cloth, paper, and metal may be used as materials in the structure of the sections forming parts of my houses. It will be understood that the principles involved in my invention may be embodied in 40 the building of out-houses and houses for birds and beasts. It will also be understood that the principles before described can be embodied in the construction of two-story houses.

Having thus described my invention, what I 45 claim as new is—

1. In a house, the combination, with the floor-joists, of the floor placed thereon and cleats secured to said floor and depending therefrom on opposite sides of the joists and 45 forming grooves in which said joists are seated, substantially as and for the purposes specified.

2. In a house, the combination, with the floor-joists and the floor thereon, of the sides 50 rested on the joists against the edges of the floor and the spikes driven into said joists outside of the sides, substantially as set forth.

3. In a house, a section or part formed of a 55 number of boards and provided with cleats fixed to said boards, whereby to secure them together, and arranged in pairs, the cleats of each pair being slightly separated, forming a groove between them, substantially as set forth.

4. In a house, a section or part formed of a 60 number of boards and provided with cleats secured to said boards and arranged in pairs, the cleats of each pair being separated, forming grooves, and such cleats being extended at one end past the section to which they are se- 65 cured, whereby to lap the adjacent section, substantially as and for the purposes specified.

5. In a structure substantially as described, a section or part provided with cleats secured transversely to it, such cleats terminating at 70 one end a distance in from one edge of the section as distinguished from extending to a point flush with said edge, and being extended at their opposite ends beyond the opposite edge of such section, substantially as set forth. 75

6. The combination of the floor, the ends, the sides, one of which is formed in sections and has its upper section overlapping the upper end of the other side, the lower edge of 80 said overlapping section being hinged, where- by such section may be opened, substantially as set forth.

7. In a structure substantially as described, the end piece having inclined edges, combined with the clasp fitted thereover and engaging 85 said edges, substantially as set forth.

8. The combination of the rafters, the end pieces, and the sides having cleats secured to their under sides, forming grooves fitted to receive the said end pieces and rafters, substan- 90 tially as and for the purposes specified.

9. The combination of the floor having 95 cleats, forming a groove fitted to receive the end, the end having inclined edges, the clasp fitted over said end and forming a guide for the upper end of the door, and the door, sub- stantially as and for the purposes specified.

10. The improved structure herein de- 100 scribed, consisting of the floor-joists set edge- wise the floor formed in sections, such sections being provided in their under sides with cleats arranged in pairs, forming grooves, and extended at one end past the sections to which they are secured and lapping the adjacent sections, the 105 cleats secured on the upper side of the floor near its ends and arranged in pairs, forming grooves to receive the ends of the structure, the ends having inclined edges, the braces fitting over said ends and forming a guide for the doors, the doors, and the sides, substan- 110 tially as and for the purposes specified.

DRUMMOND WELBURN.
